PORTABLE CUTTING MACHINE

Arthur B. Thompson and William D. Graves,
Seattle, Wash., assignors, by direct and mesne
assignments, to International Register Com-
pany, Chicago, Ill., a corporation of Illinois

Application June 30, 1928, Serial No. 289,394
Renewed December 17, 1934

10 Claims. (Cl. 164—75)

Our invention relates to machines designed for cutting sheet material and consists of a portable, power driven device, operable as a hand tool and capable of cutting sheet material in any pattern desired.

The object of our invention is to produce a device of the sort which shall be of a simple, cheap and durable construction, easily manipulated and also one in which the center of gravity is low so that it will be difficult to overturn.

The specific purpose for which this machine has been designed, is the cutting of "Beaver board". It is, however, equally well adapted to the cutting of a wide range of materials.

15 In the accompanying drawing we have shown the machine constructed in conformity with that of one which we have built and practically operated.

Figure 1 is a side elevation of the machine.
20 Figure 2 is a front elevation.

Figure 3 is a vertical section taken on a plane which includes the reciprocating knife-carrying bar and the head of the machine.

25 Figure 4 is a plan of the cutting parts of the machine, the head being in section through its lower part.

Figure 5 is a sectional plan of the head illustrating the means employed to hold the cutting bar from turning.

30 The machine organized as illustrated is mounted upon a flat base 1, which has an opening 10 towards one end in which the cutter operates. This base is designed to rest upon the material being cut and to be slid thereover after the manner of movement of an iron over cloth.

The base has mounted thereon a post 2, towards the top of which is journaled a pulley 20 carrying at one end of its shaft a crank disk or arm 21 and a crank pin 22 to which is connected a connecting rod 23. This rod is connected by a ball-and-socket joint 24 with the upper end of the knife or cutter carrying bar 25, which bar is mounted for vertical reciprocation in a guide 26 which projects from the post or head 2.

45 Secured to the lower end of bar 25 is a cutter carrying head 3, having secured thereto the knife or cutter 30. The latter is offset to one side of the axis of the reciprocating bar 25 and under certain conditions may swing said bar 25 about its axis. The opening 10 in the base plate is of a size to permit such swinging.

50 The cutter head 3 has mounted thereon for vertical reciprocation a rod 31 which functions as an operating guide and a presser foot. It is held down by springs 32 so as to be at all times in contact with the work.

55 The pulley 20 is turned from a small pulley 41 through a belt 42, pulley 41 being on the shaft 40 of a small electric motor 4 mounted upon the base plate 1. Any other suitable means for con-

nected the motor with the pulley 20 may be employed. In the drawing 5 represents the sheet being cut.

Connecting the upper part of the post or head with casing of motor 4, is a bar 6 which functions as a handle whereby to control the device.

It may at times be desirable to prevent turning of the reciprocating bar 25. In Figure 5 we have shown how this may be done. Passing through the guide arm 26, transversely of and to slightly intersect the bore which receives the bar 25, is a bore in which is mounted a locking bar 7. This bar has a flat spot 70 on one side positioned to register with the bar 25, and bar 25 has a similar flat section 71 of a length corresponding with the length of its stroke.

When locking bar 7 is turned to present its flat spot to the bar 25, the bar 25 may turn freely. When, however, the locking bar 7 is turned to present its uncut side to the bar 25, which can be done only when the flat spot 71 is toward bar 7, the bar 25 may reciprocate but cannot turn. To hold the locking bar 7 in adjusted position its projecting end may be given two flat surfaces 75 and 76 which may be engaged by a spring arm 72. The locking bar 7 may be given a bent end to form an operating arm 73.

One object we have had in mind in designing this machine is to keep the center of gravity of the machine low, so that danger of tipping over is minimized. To this end we have placed the motor close down to the base plate and have extended the drive up along the post, as by the belt 42. We have also located the handle above the motor, supporting one end from the motor casing and the other from the post or head, 2. This keeps the center of gravity low, permits use of a light post or head 2, as it has no particular weight to carry, keeps the view of the working point unobstructed by the motor and keeps the handle 35 uncovered and engageable without interference of other parts.

When commencing a cut, the device is placed upon the material to be cut, the base 1 resting upon its upper surface, and acting as a stripper, 45 to prevent the material rising with the cutter as the latter reciprocates. The presser 31 also functions as a local stripper. Now the handle 6 is grasped and the device moved bodily along the line of cut marked on the material. Since the cutter 30 and presser 31 are offset from the axis of the cutter bar 25, and normally are free to swivel thereabout, the drag of the material on the presser 31, with which it is always in contact, causes them to lie directly rearwardly of the direction in which the axis of the cutter bar 25 happens to be moving. Thus, by moving the device, through the handle 6, to one side or the other, or backwards, the presser and the cutter always drag behind the axis of the bar 25, and 60

are caused to turn and follow any given curve or line. The drag of the presser 31, behind the cutter 30, insures that the line of forward movement of the cutter will always lie substantially in a line which includes the axis of the presser and the bar 25, which latter is in advance of the presser 31.

What we claim as our invention is:

1. A cutting machine having a base adapted to rest upon and move over the work, a motor mounted upon the base, a head extending upward from one end of the base, a cutter bar mounted for reciprocation upon said head, means for reciprocating said bar by the motor, a cutter carrying head mounted upon the cutter bar to swing about the axis of said bar, a cutter carried by said head laterally spaced from its pivot axis, and means for locking said head against swinging when desired.
2. In a portable cutting machine of the type described, a reciprocating cutter bar, a cutter head mounted to swing freely about the axis of said cutter bar, a cutter carried upon said cutter head laterally spaced from said bar, and a locking key carried by said head adjustable to lock said cutter head against turning upon the cutter bar axis or to swing freely thereon as desired.
3. In a cutting machine of the character described, a base having a smooth planar under surface of considerable extent and adapted to rest upon and move over the work, a motor mounted on the base, a head extending upward from one end of the base, a cutter bar mounted for reciprocation upon said head, driving connections between said bar and said motor comprising means permitting free turning of said bar on its axis, a cutter carrying head secured upon the lower end of the cutter bar, a cutter carried by said head eccentric to said bar, and means for locking said bar against turning when desired.
4. In a cutting machine of the character described, a base having a smooth planar under surface of considerable extent and adapted to rest on and move over the work, a motor mounted on the base, a head extending upward from one end of the base, a cutter bar mounted for reciprocation upon said head, driving connections between said bar and said motor comprising a connecting rod and a ball and socket connection between said rod and the upper end of said bar permitting free turning of the latter on its axis, a cutter carrying head secured upon the lower end of the cutter bar, a cutter carried by said head eccentric to said bar, and means for locking said bar against turning when desired.
5. In a cutting machine of the character described, a base having a smooth planar under surface of considerable extent and adapted to rest on and move over the work, a motor mounted on the base, a head extending upward from one end of the base, a cutter bar mounted for reciprocation upon said head, driving connections between said bar and said motor comprising means permitting free turning of said bar on its axis, a cutting tool secured to the lower end of said bar for reciprocation and turning movement there-

with, and means for turning said bar on its axis in accordance with change in direction of movement of said base over the work.

6. In a cutting machine of the character described, a base having a smooth planar under surface of considerable extent and adapted to rest on and move over the work, a motor mounted on the base, a cutter bar mounted for reciprocation substantially perpendicular to said base and free to turn on its axis, driving connections between said motor and said bar, a cutting tool secured to the lower end of said bar for reciprocation and turning movement therewith, and means for turning said bar on its axis in accordance with change in direction of movement of said base over the work.

7. In a cutting machine of the character described, a base having a smooth planar under surface of considerable extent and adapted to rest on and move over the work, a motor mounted on the base, a cutter bar mounted for reciprocation substantially perpendicular to said base and free to turn on its axis, driving connections between said motor and said bar, means for securing a cutting tool to the lower end of said bar for reciprocation and turning movement therewith, and means for turning said bar on its axis in accordance with change in direction of movement of said base over the work.

8. In a cutting machine of the character described, a base having a smooth planar under surface of considerable extent and adapted to rest on and move over the work, a motor mounted on the base, a cutter bar mounted for reciprocation substantially perpendicular to said base and free to turn on its axis, driving connections between said motor and said bar, and means for securing a cutting tool to the lower end of said bar for reciprocation and turning movement therewith.

9. In a cutting machine of the character described, a base having a smooth planar under surface of considerable extent and adapted to rest on and move over the work, a motor mounted on the base, a cutter bar mounted for reciprocation substantially perpendicular to said base and free to turn on its axis, driving connections between said motor and said bar, means for securing a cutting tool to the lower end of said bar for reciprocation and turning movement therewith, and means for locking said bar against turning when desired.

10. In a cutting machine of the character described, a base having a smooth planar under surface of considerable extent and adapted to rest on and move over the work, a motor mounted on the base, a cutter bar mounted for reciprocation substantially perpendicular to said base and free to turn on its axis, driving connections between said motor and said bar, a cutter carrying head secured to the lower end of said bar for reciprocation and turning movement therewith, a cutter carried by said head eccentric to said bar, and means for locking said bar against turning movement when desired.
